UNITED STATES PATENT OFFICE.

BERT STEELE PARSONS AND WILLIAM ARCHIE FREEMAN, OF HARRISONVILLE,
MISSOURI.

MAGAZINE-FIREARM.

1,939,182.

Specification of Letters Patent. Patented Sept. 24, 1912.

Application filed June 15, 1912. Serial No. 703,963.

To all whom it may concern:

Be it known that we, BERT S. PARSONS and WILLIAM A. FREEMAN, citizens of the United States, residing at Harrisonville, in the 5 county of Cass, State of Missouri, have invented a new and useful Magazine-Firearm, of which the following is a specification.

The present invention relates to improvements in magazine fire arms, the primary object of the invention being the provision of a magazine extension for the usual magazine of a repeating fire-arm, and more particularly a repeating shot gun.

A further object of the present invention 15 is the provision of a magazine extension adapted to be placed detachably upon the end of the usual magazine of a repeating shot gun, the same being provided with a spring and a coupling member for connection to the outer end of the usual magazine, so that the two springs will co-act to properly feed the shells to the breech mechanism of the fire-arm, the extension being readily applied or removed as desired.

25 With the foregoing and other objects in view which will appear as the description proceeds, the invention resides in the combination and arrangement of parts and in the details of construction hereinafter described 30 and claimed, it being understood that changes in the precise embodiment of the invention herein disclosed can be made within the scope of what is claimed without departing from the spirit of the invention.

35 In the drawings—Figure 1 is a side elevation of a repeating shot gun with the magazine extension connected thereto. Fig. 2 is a longitudinal sectional view through the complete extension and the adjacent end of 40 the regular magazine. Fig. 3 is a similar view of a greater portion of the regular magazine and the extension in place, the same being loaded. Fig. 4 is an elevation of 45 the complete magazine extension with the spring retaining plug in detailed position. Fig. 5 is a detail view of the spring coupling member carried by the extension.

Referring to the drawings, the numeral 1 50 designates a repeating shot gun provided with the usual shell magazine 2 having the shell follower or cap 4 disposed therein and which is normally held toward the shells S by the magazine feed spring 5 which when in use is held properly compressed by means 55 of the removable cap (not shown). The

main magazine 2 is provided with the exterior screw threads 3 for the reception of the usual cap (not shown) and also for the coupling 7 of the magazine extension 6, which is made in the form of a tube closed at the 60 outer end to form an abutting means for the auxiliary spring 12. A spring coupling member 8 is mounted slidably within the magazine extension 6, and is provided with the central web 9 which provides abutting 65 means for the respective terminals 10 and 11 of the main magazine spring 5 and the extension spring 12, respectively.

In order to retain the coupling member 8 and the spring 12 within the magazine extension 6, when the extension is not in use, the removable plug 13 is provided with the shouldered head 14 and said plug is insertible within the threaded socket of the coupling member 7.

75 From the foregoing description, taken in connection with the drawings it is evident that the present extension may be readily applied to a repeating shot gun by the removal of the usual magazine cap (not shown) and the screwing of the extension 6 so that the coupling member 7 will fit upon the threaded end 3 of the magazine 2. It is simply necessary that the outer end 10 of the spring 5 be seated within the spring coupling 8, thus in reality forming with the two springs 5 and 12 a single spring for causing the automatic feeding of the shells S through to the breech mechanism of the fire-arm. It is evident that with an extension of this character, the capacity of a repeating shot gun may be doubled, and that by reason of the simplicity of the mounting of the same, the attachment or detachment of the same 80 from the main magazine of the repeating shot gun is exceedingly simple.

85 90 95 99 100 105 110 115
What is claimed is:

1. The combination with a magazine of a fire-arm, said magazine being provided with an outer threaded end, and a spring mounted in said magazine, of a tube having an outer closed end and having co-acting threads in the opposite end to engage the threads of the main magazine to form a magazine extension, a spring disposed in said tube and in co-operation with the spring of the main magazine, and a coupling member for the adjacent ends of the magazine spring and the spring disposed normally within the tube.

2. The combination with a magazine of a fire-arm, said magazine being provided with an outer threaded end, and a spring mounted in said magazine, of a tube having an outer closed end and having co-acting threads in the opposite end to engage the threads of the main magazine to form a magazine extension, a spring disposed in said tube and in co-operation with the spring of the main magazine, and a cylindrical member provided with an oppositely disposed chamber slidably mounted in the tubular member, said chambers forming receptacles for the adjacent ends of the two springs.
- 15 3. The combination with the main magazine of a fire-arm, and a feed spring mounted therein, of an extension for the magazine comprising a tube sealed at one end and provided with means at the open end to engage the outer end of the main magazine, a spring mounted in said extension, and a spring coupling slidably mounted within the ex-

25 tension for engaging the adjacent ends of the magazine spring and the spring of the extension.

4. The combination with the main magazine of a fire-arm, and a feed spring mounted therein, of an extension for the magazine comprising a tube sealed at one end and provided with means at the open end to engage 30 the outer end of the main magazine, a spring mounted in said extension, and a tubular spring connecting member slidably mounted in the extension and provided with oppositely disposed spring receiving cham- 35 bers.

In testimony that we claim the foregoing as our own, we have hereto affixed our signatures in the presence of two witnesses.

BERT STEELE PARSONS.

WILLIAM ARCHIE FREEMAN.
